Robert Wilder, Monroe, Morris New York

Sellers Patent

The Schedule referred to in these Seller's Patent and making part of the same containing a description in the words of the late Mr. A. Wilder, formerly of this improvement for the spiral bolt for bolting flour.

In all to whom these presents shall come, Be it known that A. Wilder of Monroe Morris in the County of Livingston and State of New York have invented a new and useful spiral bolt for bolting meal or flour, and that the following is a full and exact description thereof.

This bolt should generally be made from ten to fifteen feet long and from nearly four to nearly eight inches in diameter. The shaft to which paper through the centre of this bolt should be made of pine or other light timber and be about eight inches through. The thread which winds around this shaft should be from eight to ten inches wide and made of some metallic substance such as tin copper or sheet iron and turn at an angle of about ten degrees around the shaft. The foot or bottom of this thread is set into this shaft by having a groove cut around the shaft about a half an inch deep. There is also troughs or flanges cut and turned up on the bottom of the thread for the purpose of holding them to the shaft around the outer edge of the thread there is a hoop or ribband one inch wide and three fourths of an inch thick and made of tough hard wood with a groove in the under side to admit the thread about one fourth of an inch this is fastened to the thread by means of pine paper round it and through the one edge of the thread so that ribband is placed the bolting cloth over the whole then and following the ribband is put a narrow strip of leather through which nail are driven which holds the bolting cloth firmly to the ribband. The cloth is fastened at each end by means of iron plates made in the following manner. Around the end of the top

9292/2 X

is a collar or band with four arms, U-shaped and on the ends of
these arms is fastened the iron hoop. The ^{same} fine iron wire is wound around the
collar, and this is drawn the ends of the bolting cloth, & fastened by
having another iron hoop, made to sit firmly over the hoop just
fastened by the arms and bolting cloth. These two hoops are ~~so~~ then
screwed together, which holds the ends of the cloth firmly. The meal
or flour, being admitted into the head of a fifteen foot bolt, would
travel through a space of about one hundred and fifty feet, before
coming out at the tail.

The advantage then which this spiral bolt possesses
over any other is in containing the meal longer in the bolt and
carrying it through a much greater space - the small quantity of
meal also that is admitted between the intermediate threads is
carried separately through from the head to the tail of the bolt.
Consequently it falls off much more effectually.

What I claim is, my own invention
and not previously known in the above described machines
the spiral or coil around which the bolting cloth is fastened
and the fastening at the ends.

Andrew A. Wilder
